US00D661563S

(12) **United States Design Patent**
Wilke

(10) **Patent No.:** **US D661,563 S**
(45) **Date of Patent:** **** Jun. 12, 2012**

(54) **POLISHING MACHINE**

(75) Inventor: **Dirk Wilke**, Grabenstetten (DE)

(73) Assignee: **Metabowerke GmbH**, Nürtingen (DE)

(**) Term: **14 Years**

(21) Appl. No.: **29/407,787**

(22) Filed: **Dec. 2, 2011**

(30) **Foreign Application Priority Data**

Jun. 7, 2011 (EM) 001873852-0001

(51) **LOC (9) Cl.** **08-01**

(52) **U.S. Cl.** **D8/61**

(58) **Field of Classification Search** D8/61,
D8/62, 67, 69; 81/57, 57.11, 57.14, 57.26,
81/429, 464, 469; 173/2, 170, 176, 181

See application file for complete search history.

(57) **CLAIM**

The ornamental design for a polishing machine, as shown and described.

DESCRIPTION

FIG. 1 is a perspective view;
FIG. 2 is a front elevational view;
FIG. 3 is a rear elevational view;
FIG. 4 is a right side elevational view;
FIG. 5 is a left side elevational view;
FIG. 6 is a top plan view; and,
FIG. 7 is a bottom plan view.
